UNITED STATES PATENT OFFICE.

WILLIAM H. HART, OF NEW BRITAIN, CONNECTICUT.

DESIGN FOR A HINGE-LEAF.

SPECIFICATION forming part of Design No. 23,477, dated July 17, 1894.

Application filed April 11, 1894. Serial No. 507,181. Term of patent 14 years.

To all whom it may concern:

Be it known that I, WILLIAM H. HART, a citizen of the United States, residing at New Britain, in the county of Hartford and State of Connecticut, have invented and produced a new and original Design for a Hinge-Leaf, of which the following is a specification, reference being had to the accompanying drawing, forming part thereof, in which the figure 5 is a front view of a strap-hinge, the leaves of which show my design.

A designates one of the leaves and B the companion leaf, both having the ordinary tapering contour with rounded ends. Each leaf 5 is provided with an opening whose general contour is that of the leaf itself but of a smaller

size, the opening 2 in the leaf A being in the form shown forked at its wider end and the opening 3 in the leaf B being in the form shown single and narrow at the wider end of said leaf B. In both of these hinge leaves, the body is provided by the sides of the opening with inwardly projecting bosses 4 curved on their edge and adjacent to said bosses I form the screw holes 5. 25

What I claim is—

The design for a hinge leaf, herein shown and described.

WM. H. HART.
